UNITED STATES PATENT OFFICE.

GEORGE F. ECKART, OF MISHAWAKA, INDIANA, ASSIGNOR TO AUTOMATIC STEMME COMPANY, OF CHICAGO, ILLINOIS, A CORPORATION OF DELAWARE.

SHAKING ROLL.

Application filed May 26, 1923. Serial No. 641,594.

To all whom it may concern:

Be it known that I, GEORGE F. ECKART, a citizen of the United States, residing at Mishawaka, in the county of St. Joseph and 5 State of Indiana, have invented new and useful Improvements in Shaking Rolls, of which the following is a specification.

This invention relates to shaking rolls which are particularly adapted to be used 10 between adjacent bars of stripping rolls such as are employed in my tobacco stemming machine Serial No. 519,973, filed the 5th day of December 1921.

The invention is fully described in the 15 following specification and shown in the accompanying drawings in which:

Figure 1 is an enlarged partial front elevation showing a pair of shaking rolls,

Fig. 2 is a front elevation of one of the 20 disks composing the same, and

Fig. 3 is a perspective view of a spacer.

The embodiment illustrated comprises two parallel shafts 10 and 11 which are journaled in a suitable frame 12, and have 25 meshing gears 13 and 14 keyed thereon so that the two shafts are driven in opposite direction and at the same speed. End collars 15 are secured upon these shafts as by means of pins 16. Disks 17 and beveled 30 spacers 18 are horizontally placed on these shafts and the whole retained on the opposite end of the shafts by means of similar end rolls 15. The shafts 10 and 11 are provided with keys 19 which engage key-ways 35 17^a and 18^a in the disks and spacers respectively.

It will thus be seen that all the disks 17 on each shaft will be inclined in the same direction. The gears on the shafts 13 and 40 14 are then caused to mesh with the disks aligned as shown in Fig. 1, which forms spaces 20 therebetween. As these shafts are revolved these spaces oscillate back and forth lengthwise of the shafts.

In operation these shafts are placed one 45 above the other between two sets of rolls in the tobacco stemming machine so that as tobacco stems pass through the spaces 20 they are given a rapid shaking action which 50 causes any loose particles of tobacco leaves

to be shaken therefrom thus preventing it from being caught and drawn into the next pair of stripping rolls. To increase this separating action these rolls are preferably rotated so that the portions of the disks in 55 contact with the tobacco stems is moving in a direction opposite from that of the stem itself which is being propelled by the stemming rolls.

While I have shown and described certain 60 embodiments of my invention, it is to be understood that it is capable of many modifications. Changes therefore in the construction and arrangement may be made without departing from the spirit and 65 scope of the invention as disclosed in the appended claims, in which it is my intention to claim all novelty inherent in my invention as broadly as possible in view of the prior art. 70

What I claim as new and desire to secure by Letters Patent, is:

1. In combination, a pair of parallel shafts adapted to be driven in opposite directions, each shaft having spaced inclined 75 disks whereby when tobacco stems are fed through said disks, said stems are given a lateral shaking motion.

2. In combination, a pair of parallel shafts adapted to be driven in opposite directions, each shaft having spaced inclined 80 disks whereby when tobacco stems are fed through said disks, said stems are given a lateral shaking motion, said disks being so positioned that each disk on one shaft is 85 always substantially in alignment with a corresponding disk on the other shaft.

3. In combination, a pair of parallel shafts adapted to be driven in opposite directions, each shaft having spaced inclined 90 disks whereby when tobacco stems are fed through said disks, said stems are given a lateral shaking motion, said disks being so positioned that the adjacent edges of one set of disks are substantially opposite the 95 edges of the other set of disks, whereby nearly enclosed spaces are formed which reciprocate longitudinally of the shafts as these shafts rotate.

GEORGE F. ECKART.
